UNITED STATES PATENT OFFICE.

LUIGI VIEZZI, OF JERSEY CITY, NEW JERSEY.

VICE.

1,027,941.

Specification of Letters Patent.

Patented May 28, 1912.

Application filed July 15, 1911. Serial No. 638,626.

To all whom it may concern:

Be it known that I, LUIGI VIEZZI, a subject of the King of Italy, and a resident of Jersey City, in the county of Hudson and 5 State of New Jersey, have invented a new and Improved Vise, of which the following is a full, clear, and exact description.

My invention relates to vises, and has for its object to provide one having a jaw with 10 an arm disposed in a guideway, the arm extending through an opening in a lever fulcrumed to a beam which is held yieldingly in one direction by a spring, the lever normally gripping the arm, and means being 15 provided for operating the lever, to permit the arm on the jaw to move freely through the opening in the lever and to move the beam and with it the lever, arm and jaw, so also that when freed the spring may throw 20 the beam back and with it the lever, arm and jaw, to obtain a firm grip.

Other objects of the invention will appear in the following specification, in which the preferred form of my invention is described.

25 Similar reference characters refer to similar parts in the several parts of the drawings, in which—

Figure 1 is a sectional elevation of my invention; Fig. 2 is an inverted plan view of 30 Fig. 1; Fig. 3 is a fragmentary end view of Fig. 1; Fig. 4 is an enlarged view showing the lever with the opening through which extends the arm on the jaw, the arm being shown in section; Fig. 5 is an elevation 35 showing a modified form of the invention; Fig. 6 is an inverted plan view of Fig. 5; Fig. 7 is a fragmentary view showing the means for freeing the arm from the jaw shown in Figs. 5 and 6, and Fig. 8 is an enlarged fragmentary view showing the manner 40 of connecting the spring with the bell crank lever illustrated in Fig. 7.

By referring to the drawings it will be seen that a frame 5 is provided, having a 45 guideway 6 in which is disposed a hollow arm 7 secured to a jaw 8. A companion jaw 9 is provided and is preferably integral with the guideway 6. Disposed in the hollow arm 7 and extending into the guideway 6 there is a spring 10 for holding the jaw 8 yieldingly away from the jaw 9. A rod 11 is secured to the hollow arm 7 and projects through an opening in the head 12 of the end of the guideway. A nut 13 is provided 50 for meshing with the threaded terminal of the rod 11, to abut against the

head 12 and limit the movement of the rod 11 and the hollow arm 7 relatively to the said head 12.

To the frame 5 there is secured a depending guideway 14, in which a beam 15 is disposed, a strap 16 being secured to one end of the beam 15 and being disposed around a plurality of spring members 17, these spring members 17 resting on the flanges 18 of a bracket 19, with their terminals 20 pressing against the said bracket. Through the beam 15 there is a vertical opening 21, in which is disposed a lever 22, this lever 22 being also disposed through an opening 24 in the frame 5 and having an opening 23 through which extends the hollow arm 7. A leaf spring 25 is secured to the beam 15 and presses against the lever 22 above the beam 15, to hold it normally obliquely and 70 in engagement with the top of the hollow arm 7. A shaft 26, journaled in bearings in flanges 27 is provided, said flanges 27 being integral with the guideway 14, and mounted to rock on the said shaft 26 there 75 are two bell crank levers 28 and 29. The bell crank lever 28 is connected by a link 30 with the lower terminal of the lever 22, and the bell crank lever 29 is connected by a link 31 with the beam 15. Links 32 having 80 stirrups 33 are articulated to the levers 28 and 29 by which the levers may be readily operated by the foot of the mechanic.

In using the invention, the lever 28 is operated by its stirrup 33 which, by means of 90 the link 30, draws the lower terminal of the lever 22 forward, so that the upper terminal of the lever 22 will be moved rearward and in position to permit the arm 7 to move freely in the guideway. After this has been 95 done, it will be found that the spring 10 will force the hollow arm 7 and the jaw 8 outward, so that a member may be readily inserted between the jaws 8 and 9. When this has been done the jaw 8 is pushed inward, and at the same time the lever 29 is 100 operated by its stirrup 33. When the jaw 8 has been pushed inward and the member is held snugly between the jaws 8 and 9, the lever 29 is freed, so that the beam 15 will be 105 moved rearward by means of the springs 17, to hold the member firmly between the jaws.

It will be seen that the upper terminal of the lever 22 is bent forward, and when the 110 parts are in normal position the spring 25 will press the upper terminal of the lever 22

forward, so that the hollow arm 7 will be gripped by the lever 22 at the upper portion of its opening 23, but when the bell crank lever 28 is operated by means of the stirrup 33, the upper terminal of the lever 22 will be moved rearward, so that the arm 7 may be moved freely therein.

In the modified form of the invention shown in Figs. 5, 6 and 7 of the drawings, 19 the beam 34 is disposed for traveling in the guideway 35 and is held yieldingly in one direction by means of the springs 36, which correspond in all particulars with the springs 17 shown in Fig. 1 of the drawings, 15 a strap 37 being secured to the beam 34, this strap being disposed around the springs 36 intermediate of their terminals. In a guideway 38 in the frame 39, a jaw 40 is disposed for travel, this jaw 40 having a 20 rack 41 which extends through a carriage 42 having bearings in which a pinion 43 is journaled, said pinion meshing with the rack 41. It will be understood that by rotating the pinion 43 the jaw 41 may be 25 raised or lowered, as desired. The carriage 42 has transverse members 42^a which engage the top and the bottom of the beam 34, while permitting the carriage 42 to travel on the said beam. A depending bracket 44 30 is secured to the frame 39 and a bell crank lever 45 is fulcrumed to the said bracket, one arm of the said bell crank lever being connected to the beam 34 by means of a link 46, a link 47 being fulcrumed to the other 35 arm of the said bell crank lever and a stirrup 48 being secured to the bottom of the said link 47. Disposed to slide in guideways 49 there is an arm 50, to which is secured a jaw 51^a. This arm 50 extends through an opening 51 in a lever 52. One arm of this lever 52 is connected with the beam 34, by means of a link 53, the other arm of this lever 52 being connected with a bell crank lever 54 by means of a link 55. To the bell 45 crank lever 54 there is articulated a link 56, having a stirrup 57 at its lower terminal. In using this form of the invention, the link 47 is drawn downward by means of its stirrup 48 when the jaw 40 is moved to the 50 left with its carriage 42, so that a member may be held between the jaw 40 and the companion jaw 40^a. When the member is held snugly between the jaws 40 and 40^a the link 47 is freed, which permits the 55 springs 36 to move the beam 34 to the left and with it the carriage 42 and the jaw 40, the carriage 42 being prevented from slipping to the right by the pressure on the top of the jaw 40, which presses the top of the 60 carriage 42 slightly rearwardly relatively to the beam 34, so that the transverse members 42^a of the carriage will engage the top and the bottom of the beam and prevent the carriage 42 from slipping. The carriage 42 65 may be moved to the right when desired by

pressing down on the link 47 which will operate the bell crank lever 45 to draw the beam 34 to the right by means of the link 46, and when the beam 34 is drawn to the right it will carry with it the carriage 42, and the 70 jaw 40, sufficiently far to relieve the jaw 40 from the pressure against a member clamped between the jaws 40 and 40^a, and when this has been done the carriage 42 may be moved farther to the right without 75 difficulty. When the link 56 is moved downward by means of the stirrup 57 it operates the bell crank lever 54 which, by means of the link 55, operates the right-hand terminal of the lever 52 through the opening 51 in 80 which the arm 50 is disposed. When the said right-hand terminal of the lever 52 is operated, the lever 52 is disposed at right angles to the arm 50, and the said arm 50 may be moved freely in the said opening 51, 85 to permit of the movement of the jaw 51^a to or from the frame 39, as may be desired. When the jaw 51^a has been moved in the direction of the frame 39 to the desired position, the link 56 is released and the right 90 terminal of the lever 52 moves back to its former position, so that the said lever 52 will be disposed obliquely relatively to the arm 50, to grip the arm 50 at the sides of the opening 51. It will also be seen that by 95 moving the link 47 downward, the arm 50 and the jaw 51^a may be freed from the lever 52, since, when this link 47 is moved downward, it will draw the beam 34 to the right, which in turn will move the upper 100 terminal of the link 53 to the right and will draw toward the beam 34 the left terminal of the lever 52, and as this will move the lever 52 so that it will be at right angles to the arm 50, the said arm 50 may be moved 105 freely in the opening 51 in the said lever 52, to permit of the movement of the jaw 51^a to the desired position. A spring 60 is provided for holding the bell crank lever 54 yieldingly in position with the right terminal of the lever 52 upward. 110

Having thus described my invention, I claim as new and desire to secure by Letters Patent:

1. In a vise, a frame having a guideway, 115 a jaw having an arm disposed for moving in the guideway, a beam movable relatively to the frame, a lever fulcrumed to the beam and having an opening through which the arm is disposed, a spring for holding the beam yieldingly in one direction, a spring for holding the lever at its opening against the arm, means for operating the lever, and means for moving the beam against the tension of the first-mentioned spring. 120

2. In a vise, a frame having a guideway, a jaw having an arm disposed for moving in the guideway, a beam movable relatively to the frame, a lever fulcrumed to the beam and having an opening through which the 125

- arm is disposed, a spring for holding the beam yieldingly in one direction, and a spring for holding the lever at its opening against the arm.
5. 3. In a vise, a frame having a guideway, a jaw having an arm disposed for moving in the guideway, a lever having an opening through which the arm extends, resilient means for normally holding the lever at its opening against the arm, and a lever fulcrumed to the frame, one arm of which is articulated to the first-mentioned lever to move it so that the arm may move freely through the opening in the lever.
10. 4. In a vise, a frame having a guideway, a jaw having an arm disposed for moving in the guideway, a beam movable relatively to the frame, means for holding the beam normally in a predetermined position relatively to the frame, a lever fulcrumed to the beam and having an opening through which the arm is disposed, resilient means for normally holding the lever at its opening against the arm, and means for operating the lever.
15. 5. In a vise, a frame having a guideway, a jaw having an arm disposed for moving in the guideway, a beam movable relatively to the frame, a lever fulcrumed to the beam and having an opening through which the arm is disposed, and means for holding the beam in one direction.
20. 6. In a vise, a frame having a guideway, a jaw having an arm disposed for moving in the guideway, a beam movable relatively to the frame, a lever fulcrumed to the beam and having an opening through which the arm is disposed, and a spring for holding the beam in one direction.
25. 7. In a vise, a frame having a guideway, a jaw having an arm disposed for moving in the guideway, a beam movable relatively to the frame, a lever fulcrumed to the beam and having an opening through which the arm is disposed, means for holding the beam in one direction, a lever fulcrumed to the frame, and a link articulated to the two levers.
30. 8. In a vise, a frame having a guideway, a jaw having an arm disposed for moving in the guideway, a beam having an opening, a lever disposed through the opening in the beam and having an opening through which the arm is disposed, a lever fulcrumed to the frame, and means connecting the second lever with the first-mentioned lever for operating the latter.
35. 9. In a vise, a frame having a guideway, a jaw having an arm disposed for moving in the guideway, a beam having an opening, a lever disposed through the opening in the beam and having an opening through which the arm is disposed, a lever fulcrumed to the frame, means for connecting the second-mentioned lever with the first-mentioned lever, for operating the latter, and a spring for holding the first-mentioned lever yieldingly in a predetermined position.
40. 10. In a vise, a frame having a guideway, a jaw having an arm for moving in the guideway, a beam movable relatively to the frame, a member having an opening through which the arm is disposed, a link connecting the beam with one end of the member, and means for holding the other end of the member yieldingly in a predetermined position.
45. 11. In a vise, a frame, a jaw secured to the frame and having a guideway with an orifice, a second jaw having a hollow arm disposed in the guideway, a spring disposed in the guideway for holding the second-mentioned jaw yieldingly away from the first-mentioned jaw, a rod secured to the arm and projecting through the orifice, and a head on the rod, for abutting against the guideway and limiting the movement of the second-mentioned jaw relatively to the first-mentioned jaw.
50. 12. In a vise, a frame, a jaw secured to the frame and having a guideway, a second jaw having a hollow arm disposed in the guideway, a spring disposed in the guideway for holding the second-mentioned jaw yieldingly away from the first-mentioned jaw, a beam movable relatively to the frame, a lever fulcrumed to the beam and having an opening through which the arm is disposed, and means for holding the beam in one direction.
55. 13. In a vise, a frame having a guideway, a jaw having an arm for moving in the guideway, a beam movable relatively to the frame, a member having an opening through which the arm is disposed, a link connecting the beam with one end of the member, a lever fulcrumed to the frame, means connecting the lever with the other end of the member, and means for holding the lever yieldingly in a predetermined position.
60. 14. In a vise, a frame having a guideway, a jaw having a member for moving in the guideway, a beam movable relatively to the frame, a spring for holding the beam yieldingly in one direction, means operable by the beam for actuating the member, a lever fulcrumed to the frame, and means connecting the lever with the beam for operating the latter.
65. 15. In a vise, a frame having a guideway, a jaw having an arm for moving in the guideway, a gripping member having an opening through which the arm is disposed, and means for holding the member yieldingly in one direction.
70. 16. In a vise, a frame having a guideway, a jaw having an arm for moving in the guideway, a member having an opening through which the arm is disposed, means for holding the member yieldingly in one

direction, a lever fulcrumed to the frame, and means connecting the lever with the member for operating the latter.

17. In a vise, a frame having a guideway, 5 a jaw having an arm disposed for moving in the guideway, a beam for moving relatively to the frame, a member having an opening through which the arm is disposed, a link connecting one end of the member 10 with the beam, a lever fulcrumed to the frame, and a link connecting the other end of the lever with the beam.

18. In a vise, a frame having a guideway, 15 a jaw having an arm disposed for moving in the guideway, a beam for moving relatively to the frame, a member having an opening through which the arm is disposed, a link connecting one end of the member 20 with the beam, a lever fulcrumed to the frame, a link connecting the other end of

the lever with the beam, a spring for holding the lever yieldingly in one direction, and a spring for holding the beam yieldingly in one direction.

19. In a vise a frame having a guideway, 25 a jaw having an arm for moving in the guideway, a pivoted member having an opening through which the arm is disposed, a lever fulcrumed to the frame, means connecting the lever with the member for operating the latter, and resilient means for holding the lever in a predetermined position.

In testimony whereof I have signed my name to this specification in the presence of 35 two subscribing witnesses.

LUIGI VIEZZI.
